HIGH-DRAFT DRAWING MECHANISM FOR SPINNING MACHINES

Kurt Quaas, Denkendorf, Germany, assignor to Zellwolle-Lehrspinnerei G.m.b.H., Denkendorf, near Esslingen (Neckar)

Continuation of application Ser. No. 186,698, Sept. 26, 1950. This application Dec. 26, 1956, Ser. No. 630,571

In Germany Oct. 1, 1948
Public Law 619, Aug. 23, 1954
Patent expires Oct. 1, 1968
11 Claims. (Cl. 19—131)

This invention relates to a high-draft drawing mechanism, constructed as a double-tape drawing mechanism, for preparatory spinning and fine spinning machines, said mechanism having an independently mounted, fixed guide rail for the bottom tape and a guide yoke, mounted on the tape cradle, for the top tape.

This application is a continuation of copending application Ser. No. 186,698, filed September 26, 1950, which is now abandoned.

The best known construction of a double-tape drawing mechanism is that of Casablancas. In a widely used modification of this construction a U-shaped yoke is inserted in the tape cradle, the top tape being guided by the upper arm of said yoke, while the bottom tape is guided by its lower arm. The position of the yoke and of its two arms is determined to a considerable extent by the spindle of the top roller, since said spindle engages two guide slots on both sides of the tape cradle, the latter in its turn being pivotally mounted on the bottom roller. By adjustment of the top and bottom tape rollers for adaptation to the varying nature of the material to be spun (long or short fibres), variation of the relative position of the spindle of the top roller to that of the bottom roller is unavoidable. On this account, however, the position of the tape cradle and of the guide yoke and hence the path of the tapes in the drafting field are varied in a troublesome manner.

Furthermore, double-tape drawing mechanisms are known which consist of a combination of a single-tape drawing mechanism on the Le Blanc-Roth system, with a double-tape drawing mechanism on the Casablancas-Kassel system. In these drawing mechanisms, the lower tape is drawn over a fixed guide rail and its tension is produced by means of a tensioning roller. A tensioning roller or a guide yoke is used for guiding the top tape on the side remote from the top tape roller.

The effect of the known tensioning roller, which runs freely without bearings, is that with an inclined drafting field, it exerts a tension effect on the bottom tape through its own weight under the action of gravity. Since for reasons of spinning technique, it has to have only a relatively small diameter, it has a comparatively small weight and hence no adequate mass effect. Consequently, the tensioning roller tends to make uncontrollable movements, which may result in an oblique positioning of the roller and interference with the running of the tape. A further disadvantage of the tensioning roller is that it requires an inclined arrangement of the drafting field.

With the use of a guide yoke in the above-mentioned construction, said yoke is laid freely movable on the tape cradle and is guided solely by an upper extension engaging a guide slot in the tape cradle. Due to the force exerted by the top tape on the guide yoke, the yoke extension is pressed into the guide slot. The top tape thus determines the position of the guide yoke. If the top tape is slack, all guiding and tensioning effect of the yoke is lost.

It is an important object of the invention, to provide

2

a double-tape drawing mechanism of the kind described in the opening paragraph, the fixed guide rail for the bottom tape and the guide yoke for the top tape being connected together in a positive manner, if desired, via the tape cradle. By this means, the position of the top tape is fixed in a definite manner. For this purpose, the fixed guide rail may have an extension constructed in the form of a three-sided prism, which in the operative position engages a corresponding recess in the tape cradle.

10 The arrangement may, however, be such that disengageable movable coupling means, such as hooks and the like, are secured to the fixed guide rail and/or the tape cradle and provide the positive connection between guide rail and tape cradle. The advantage of this arrangement is that after the disengagement of the coupling means, the tape cradle may be pivoted upwardly, for example for the removal of laps or for cleaning purposes. The disengageable coupling means may consist for example of a pivoted coupling hook, which is rotatably secured to the fixed guide rail, and which, in the operative position, preferably engages the end of the guide yoke projecting from the tape cradle. At its free end, the coupling hook conveniently carries a roof-shaped extension on which, after it has been pivoted upwardly, the tape cradle may be laid, preferably by means of the end of the guide yoke projecting from it. By this means, the spinning machine attendant has both hands free for manipulations.

15 It is a further object of the invention, that the distance between the fixed guide rail and the yoke is variable by the use of different, interchangeable guide yokes. For this purpose, the yokes may have different cross-sections, for example portions machined off above or below. In this case, the position of the contact surface of 20 the two tapes is always determined by the fixed guide rail, so that the contact surface always remains invariable in its position in the drafting field, despite its dependence upon the kind of yoke used.

25 In the drawings:

30 FIG. 1 shows a double-tape drawing mechanism according to the invention, in side view,

FIGS. 2 and 3 the tape cradle with different guide yokes in each case, in front view,

35 FIGS. 4 and 5 on an enlarged scale the course of the tapes at the deflecting points, using guide yokes of different constructions, in side section.

40 FIG. 6 a double-tape drawing mechanism according to the invention, in which the positive connection is effected by means of a coupling hook, in the operative position, in side view,

45 FIG. 7 the same drawing mechanism with upwardly pivoted tape cradle, likewise in side view,

FIG. 8 the coupling hook and its mounting, in plan,

50 FIG. 9 another constructional form of a double-tape drawing mechanism in the operative position, in side view,

FIG. 10 the same drawing mechanism in front view, partly in section,

55 FIG. 11 a tape cradle, in which the disengageable connecting means consists of a spring member, in front view,

60 FIG. 12 a modified tape cradle in the upwardly pivoted position in side view,

65 FIG. 13 shows a drawing mechanism according to the invention with a two-part tape cradle and a tensioning roller holder with a tensioning roller in the operative position in side view,

70 FIG. 14 the same drawing mechanism, partly in vertical section on line A—A in FIG. 13 and partly in a view from the entry side of the material and of the tapes,

FIG. 15 the same drawing mechanism in the upwardly pivoted position in side view,

75 FIG. 16 a further constructional form of a double-

tape drawing mechanism according to the invention in side view,

FIG. 17 the same drawing mechanism in front view,

FIG. 18 another constructional form of a double-tape drawing mechanism according to the invention in side view, and

FIG. 19 the same drawing mechanism in front view.

In the double-tape drawing mechanism according to FIG. 1, the material to be spun first runs between the feed rollers 1 and 2, then between the bottom tape 3 and the top tape 4, and finally between the pair of delivery rollers 5 and 6. The bottom tape 3 is driven by the bottom tape roller 7, is drawn at the front end of the tape cradle 8 over the fixed guide rail or guide bar 9 and is tensioned by the tensioning roller 10. The top tape 4 is driven by the bottom tape 3 and runs over the top tape roller 11, which it sets in motion, and at the end of the tape cradle or cage 8 over the exchangeable yoke or guide bar 12 mounted in said cradle.

The fixed guide bar 9 has an extension 13 in the form of a three-sided prism which engages a corresponding recess in the tape cradle 8.

On placing the cage means or tape cradle 8 on the tape bottom roller 7, the cradle must be moved in such a way that the extension 13 is able to catch in the corresponding recess of the tape cradle 8. The tape cradle 8 is thereby given a definitely fixed position relatively to the fixed guide rail 9 for the bottom tape 3. Since the tape cradle 8 is at the same time the support for the guide yoke 12 of the top tape 4, a fixed association is effected between the guide rail 9 for the bottom tape 3 and the guide yoke 12 for the top tape 4, which does not alter even after a long period of working.

The degree of curvature of the top tape 4 from the surface of contact of the tapes on to the guide yoke 12 is determined by the distance of the latter from the fixed guide rail 13. In the arrangement according to FIGS. 2 and 4, a guide yoke 12 or 12a has been inserted in the tape cradle 8, the profile of said yoke by machining off the upper guiding part is of such a shape that there is a relatively short distance between the guide yoke 12 or 12a and the fixed guide rail 13. Consequently, the top tape 4 is drawn around the guide yoke 12 in a shortened curve. The path on which the bottom tape 3 and top tape 4 are in contact and on which they together guide the fibres, thereby becomes relatively long.

If, in the treatment of long-staple raw materials this path and hence the fibre control is to be diminished, a guide yoke 12b is used which, as will be seen from FIGS. 3 and 5, in this case has a machined-away profile at the bottom, such that the distance between the fixed guide rail 13 for the bottom tape and the guide yoke 12b for the top tape is comparatively greater. Consequently, the top tape 4 is now carried in a greater curve over the guide yoke 12b, so that the path on which the bottom tape 3 and top tape 4 are in contact is shortened and hence the fibre control is also diminished.

In the double-tape drawing mechanism according to FIGS. 6 to 8, a bracket 14 is secured to the fixed guide rail 9 for the bottom tape, a two-part coupling hook 15c being pivotally mounted on the said bracket and being held under the action of a spring 16 in a position in which it engages the ends of the guide yoke 12a projecting from the tape cradle 8. By this means, the positive connection between the fixed guide rail 9 for the bottom tape and the guide yoke 12c for the top tape is again established.

If, on the occurrence of laps or of the purpose of cleaning the tape track, the tape cradle is to be pivoted up, the coupling hook 15c has merely to be turned back against the action of the spring. It has on its upper end a roof-shaped extension 17, on which after its return into the position of rest the ends of the guide yoke 12c, projecting from the tape cradle 8, may be placed, so that the spinning machine attendant, after pivoting up the tape cradle, has both hands free for removing any laps or for cleaning.

In FIG. 7, the coupling hook 15c is also shown in the swung-out position. The tape cradle is also shown in the position it assumes after being pivoted up.

In FIGS. 9 and 10, the bottom tape 3 driven by the bottom tape roller 7 is again drawn over a fixed guide rail 9. Said bottom tape drives the top tape 4 and the top tape roller 11. At the deflecting point, turned away from the top tape roller 11, the top tape 4 runs over the guide rods 12e, which represent merely short rod ends, rigidly secured to the sides 18 of the tape cradle 8e. The tape cradle 8e is mounted on the spindle 19 of the top tape roller 11. Pivoted externally to the tape cradle 8e is a double-sided coupling hook 15e, which in its operative position engages behind a projection 20 provided on the guide rail 9 for the bottom tape 3. By means of this coupling hook 15e a positive connection is established via the tape cradle 8e between the guide rods 12e and the guide rail 9, thus ensuring that the distance between the guide rods 12e and the guide rail 9 and their position relatively to each other remains always the same during operation, so that disturbances of the drafting process from that quarter are excluded. In addition the coupling hook 15e also has more particularly the effect that any torque exerted by the spindle 19 of the top tape roller 11 on the tape cradle 8e is taken up by the projection 20 secured to the guide rail 9, and consequently no rotation of the tape cradle 8e can occur.

In the tape cradle according to FIG. 11, for securing the position of the cradle relatively to the guide rail and more particularly also for taking up any torque exerted on the cradle, a spring member 15f is provided and is rigidly connected to the guide rail 9 by means of a bar 21. The spring member 15f is pawl-shaped at its free end, and by means of the pawl 22 engages a catch 23 on the side 18f of the tape cradle 8. The effect of this arrangement is that the spring member 15f, after the tape cradle 8f has been moved to the operative position is automatically engaged in the latched position, while when the tape cradle 8f is pivoted up, the spring member is automatically disengaged.

In FIG. 12, the tape cradle or cage means is shown in the upwardly pivoted position. The cradle sides 18f have extensions 24, which after the tape cradle 8f has been pivoted up, serve as stops against the top feed roller 2.

The drawing mechanism according to FIGS. 13 to 15 shows fundamentally the same construction as the drawing mechanisms described hereinbefore. In this case, however, the tape cradle is formed in two parts, consisting of an upper part 25 and a lower part 26. The upper part 25 is mounted on the spindle 19g of the top tape roller 11 in such a manner that with its plane supporting surfaces 27, embracing the spindle 19g, it touches the spindle only tangentially, thereby providing a reliable and definite support. Pivoted to the upper part 25 of the tape cradle, externally on both sides, is a coupling hook 15g, which in its operative position engages a catch 28. The catch 28 is formed by the upper lateral extension of the vertical arm 29 of a support 30 for the bottom tape, said support being fixed to the guide rail 9. The coupling hook 15g establishes via the upper part 25 of the tape cradle a positive connection between the guide yoke 12g and the guide rail 9, which ensures that the distance between the guide yoke 12g and the guide rail 9 and their position relatively to each other remains always the same during operation, thereby also ensuring a satisfactory and uniform carriage or guiding of the fibre material by the tapes. The coupling hook 15g furthermore prevents any torque exerted by the spindle 19g on the upper part 25 of the tape cradle altering the position of the upper part 25 in an undesired manner. If such a torque occurs, it is taken up by the catch 28.

The catch 28 is so arranged that it lies in the direction of the effective tension of the top tape, so that a satisfactory positive connection is established by the bent end 31 of the coupling hook 15g engaging said catch. The

coupling hook 15g is secured in the operative position by the hook end 31 abutting against the guide rail 9.

The coupling hook 15g is constructed as a double lever in such a manner that its upper free arm 32 serves for its actuation. The adjacent wall 33 of the upper part 25 has a recess 34, so that there is no impediment to the actuation of the arm 32.

The lower part 26 of the tape cradle is mounted on the spindle 35 of the bottom tape roller 7. It is constructed in such a manner that both the top tape 4 and the bottom tape 3 are securely guided by it from their entry point behind the guide rail 9. The bottom tape 3 is tensioned by a tensioning roller 36 which is mounted in the slot 37 of the tensioning roller holder 38. In consequence of the satisfactory guiding of the bottom tape 3 by the lower part 26 of the tape cradle, the tensioning roller 36 does not need to have the otherwise usual collar. For assisting uniform tape movement, the tensioning roller frame is constructed so that its sides 39 project on all sides over the periphery of the tensioning roller 36.

In order to limit any movement of the lower part 26 caused by the tapes 3 and 4 or by its own weight, stops 40 are provided, these being formed by lateral extensions of the vertical arm 29 of the tape support 30.

The lower part 26 has, on its upper edge, a nose 41, corresponding to which is a recess 42 on the lower edge of the upper part 25. The nose 41 limits any movements of the upper part 25 after removal of the loading support in the case of floating rollers or pressure rollers without lateral guiding, which is of particular importance in the case of inclined drawing mechanisms.

As will be seen from FIG. 15, the upper part 25, after it has been pivoted up by release of the coupling hook 15g, has an absolutely reliable position. This is accomplished by the fact that the upper part 25 rests with a suitable surface 43 of the side 33 on an extension 44 of the side 45 of the lower part 26. The effective surfaces of the top tape 4 and bottom tape 3 are thus made conveniently accessible for attention and cleaning.

In the double tape drawing mechanism according to FIGS. 16 and 17, the tape cradle is again made in two parts. It consists of the lower part 76 and the upper part 75. The lower part 76 is fixed by means of the screw 46 to the fixed guide rail 69. The upper part 75 is mounted on the spindle 19 of the top tape roller 11. It comprises at its other end the guide yoke 72, by means of which the top tape 4 is tensioned and guided at the deflection point remote from the top roller 11. Both the lower cradle portion 26 and the upper part 25 are constructed so that the bottom tape 3 and the top tape 4 are reliably guided, particularly where they bear on the bottom roller 7 and the top roller 11.

Fixed to a horizontal extension 47 of the fixed guide rail 69 is a U-shaped yoke 48, which embraces from below the lower part of the tape cradle, and engages with its spring ends 22, bent to form pawls, catches 23 provided on the sides of the upper cradle part 25. In this way, between the fixed guide rail 69 and the guide yoke 72 there is established a positive connection, by means of which the position of the guide yoke 72 relatively to the fixed guide rail 69, and hence the position of the tapes 3 and 4 relatively to each other is fixed in an absolute manner.

The spring ends 22 of the U-shaped yoke 48 and the catches 23 are so constructed and arranged in detail that upon the formation of a considerable lap in the drafting field between the tapes 3 and 4, the positive connection is automatically released in consequence of the forces thereby exerted on the upper part 75 of the cradle. The latter makes a rotary movement about the spindle 19, whereby the catches 23 move past the pawls 22 and release the engagement. If the laps are not so considerable as to produce automatic release of the connection, the special construction and arrangement of the connecting

means has the effect of promoting the release of the connection as a result of the forces produced by the laps when the cradle upper part 75 is pivoted by hand.

In the double-tape drawing mechanism according to

5 FIGS. 18 and 19, a support 80 for the bottom tape 3 is secured to the fixed guide rail 9 by means of the screw 49 and supports the bottom tape 3 below the drafting field. The U-shaped yoke 98 with the spring pawl-shaped ends 22 is in this case fixed to the horizontal arm of the support 80. The spring ends 22, together with the catches 23 on the sides of the cradle upper part 85, have the same effect as described in the foregoing with reference to the corresponding arrangement in the constructional example according to FIGS. 16 and 17.

10 15 The lower part 86 of the tape cradle carries two extensions 50 by means of which, when it is being fixed to the machine, it is inserted between the inner wall of the guide rail 79 and a part of the lateral surface of the U-shaped yoke 98.

20 Having thus described the invention, what is claimed as new and desired to be secured by Letters Patent is:

25 1. A tape drawing mechanism for spinning machines, comprising, in combination, a top tape and a bottom tape; a top tape roller supporting said top tape for movement thereon; a shaft supporting said top tape roller; stationary guide means spaced from said top tape roller and supporting said bottom tape for movement thereover; a bottom cage member supported by said guide means for laterally guiding said tapes; top cage means, for 30 laterally guiding said top tape, pivotally mounted on said shaft on opposite sides of said top tape roller for free movement about said shaft, said top cage means, in its operative position, resting on said bottom cage member; a releasable lock member movably mounted on one 35 of said means and engaging the other of said means to releasably lock said top cage means with respect to said guide means, whereby said releasable lock member may be moved to unlock said top cage means without moving the latter or said bottom cage member.

40 2. In a double tape drawing mechanism for spinning machines, in combination, a stationary fixed guide rail for supporting the bottom tape for movement thereover; a bottom cage supported on said guide rail for laterally guiding the top and bottom tapes of the drawing mechanism; a substantially U-shaped lock member fixedly mounted on said guide rail and having a pair of opposite legs extending upwardly from said guide rail on opposite sides of the tapes, said legs respectively having free, 45 springy end portions bent toward each other; a top tape roller supporting the top tape for movement thereon; a shaft supporting said top tape roller; a top cage pivotally mounted on said shaft for turning movement thereabout and having a pair of opposite side walls respectively 50 engaging the top tape to laterally guide the same, said opposite side walls respectively having projecting portions engaged by said free end portions of said legs of said U-shaped lock member so that said top cage is releasably held by said lock member in a predetermined position with respect to said guide rail, whereby said top cage 55 may be automatically released from said bottom cage and guide rail if the material passing between the tapes becomes too thick.

55 3. A double tape drawing mechanism for spinning machines, comprising, in combination, top and bottom tapes; a stationary fixed guide rail supporting said bottom tape for movement thereover; a bottom tape support fixed to said guide rail; a substantially U-shaped lock member fixed to said tape support and having a pair of opposite legs extending upwardly from said tape support on opposite sides of said bottom tape, said legs respectively having springy, free end portions bent toward each other; a bottom cage mounted on said lock member and guide rail for laterally guiding said tapes; a top tape roller supporting said top tape for movement thereon; a shaft 60 supporting said top tape roller; a top cage pivotally

65 70 75 mounted on said lock member and guide rail for laterally guiding said tapes; a top tape roller supporting said top tape for movement thereon; a shaft supporting said top tape roller; a top cage pivotally

mounted on said shaft for turning movement thereabout and having a pair of opposite side walls respectively engaging said top tape to laterally guide the same and respectively having projecting portions engaged by said free end portions of said legs of said lock member so that said top cage member is held in a predetermined position with respect to said guide rail and said bottom cage, whereby said top cage will automatically move away from said bottom cage when the material passing between said tapes becomes too thick.

4. In a double tape drawing mechanism for spinning machines, in combination, a top tape and a bottom tape; top tape roller means and bottom tape roller means located adjacent and being parallel to each other and respectively cooperating with said top tape and bottom tape to guide the latter for movement; cage means connected to the machine by said bottom tape roller means and being guided by said bottom tape roller means for movement back and forth along an unchanging predetermined path between an operating position and a rest position while remaining at all times connected to the machine, said top tape being at least partly located in said cage means and being laterally guided by the latter; an upper guide bar carried by said cage means for guiding said top tape; a stationary fixed lower guide bar guiding said bottom tape and located adjacent said upper guide bar when said cage means is in its operating position and distant from said upper guide bar when said cage means is in its rest position, said lower guide bar being parallel to said upper guide bar; and releasable lock means cooperating with said cage means for releasably locking the same in said operating position thereof to locate said upper guide bar at a predetermined distance from said lower guide bar when said cage means is in its operating position.

5. In a double tape drawing mechanism for spinning machines, in combination, a top tape and a bottom tape; top tape roller means and bottom tape roller means located adjacent and being parallel to each other and respectively cooperating with said top tape and bottom tape to guide the latter for movement; cage means connected to the machine by one of said roller means and being guided by said one roller means for movement back and forth along an unchanging predetermined path between an operating position and a rest position while remaining at all times connected to the machine, said top tape being at least partly located in said cage means and being laterally guided by the latter; an upper guide bar carried by said cage means for guiding said top tape; a stationary fixed lower guide bar guiding said bottom tape and located adjacent said upper guide bar when said cage means is in its operating position and distant from said upper guide bar when said cage means is in its rest position, said lower guide bar being parallel to said upper guide bar; a pair of hooks turnably carried by said lower guide bar and having free hook ends, respectively, located adjacent said cage means when the latter is in its operating position; and means carried by said cage means and engaging said ends of said hooks for determining the operating position of said cage means and for maintaining said upper guide bar at a predetermined distance from said lower guide bar when said cage means is in its operating position.

6. In a double tape drawing mechanism for spinning machines, in combination, a top tape and a bottom tape; top tape roller means and bottom tape roller means located adjacent and being parallel to each other and respectively cooperating with said top tape and bottom tape to guide the latter for movement; cage means connected to the machine by one of said roller means and being guided by said one roller means for movement back and forth along an unchanging predetermined path between

an operating position and a rest position while remaining at all times connected to the machine, said top tape being at least partly located in said cage means and being laterally guided by the latter; an upper guide bar carried by said cage means for guiding said top tape; a stationary fixed lower guide bar guiding said bottom tape and located adjacent said upper guide bar when said cage means is in its operating position and distant from said upper guide bar when said cage means is in its rest position, said lower guide bar being parallel to said upper guide bar; and resilient, releasable catch means for resiliently and releasably maintaining said cage means in said operating position thereof to locate said upper guide bar at a predetermined distance from said lower guide bar when said cage means is in its operating position.

7. A tape drawing mechanism for spinning machines, comprising, in combination, a top tape and a bottom tape; a top tape roller and a bottom tape roller located adjacent and parallel to each other and respectively cooperating with said top tape and bottom tape to guide the latter for movement, said rollers having their peripheries spaced apart by the thickness of the belts only to provide a nip therebetween, top cage means for laterally guiding said top tape, a stationary fixed lower guide bar guiding said bottom tape, an upper guide bar carried by said cage means for guiding said top tape and located adjacent said lower guide bar when said cage means is in its operative position, said upper guide bar being parallel to said lower guide bar, said cage means being pivotally mounted on said machine for free movement in a circular path about a fixed axis between an operating position and a rest position, while remaining at all times connected to the machine, a releasable lock member for releasably maintaining said cage means in said operating position thereof to locate said upper guide bar at a predetermined distance from said lower guide bar when said cage means is in its operating position, said releasable lock member being movable to unlock said cage means before moving the latter.

8. In a mechanism as claimed in claim 7, the top cage means being supported in its operative position by the stationary fixed lower guide bar.

9. In a mechanism as claimed in claim 7, said lower guide bar extending laterally beyond the bottom tape, the cage means having side walls engageable with the lower guide bar when the cage means is in operative position, the upper guide bar being secured in said side walls.

10. A tape drawing mechanism for spinning machines, comprising, in combination, a top tape and a bottom tape; a top tape roller and a bottom tape roller located adjacent and being parallel to each other and respectively cooperating with said top tape and bottom tape to guide the latter for movement, said rollers having their peripheries spaced apart by the thickness of the belts only to provide a nip therebetween, top cage means for laterally guiding said top tape, a lower guide bar guiding said bottom tape, an upper guide bar carried by said cage means for guiding said top tape and located adjacent said lower guide bar when said cage means is in its operative position, said upper guide bar being parallel to said lower guide bar, said cage means being pivotally mounted on said machine for free movement in a circular path about a fixed axis between an operating position and a rest position, while remaining at all times connected to the machine, said upper guide bar moving at all times in a circular arc at a constant distance from said fixed axis.

11. In a mechanism as claimed in claim 10 the fixed axis on which the cage means is pivotally mounted being coincident with the axis of the top tape roller.
